UNITED STATES PATENT OFFICE

150,656

DESIGN FOR AN ADVERTISING DEVICE OR THE LIKE

John J. Reinhold, Marietta, Pa.; Albert C. Reinhold, executor of said John J. Reinhold, deceased

Application November 1, 1946, Serial No. 134,439

Term of patent 7 years

(Cl. D1—12)

To all whom it may concern:

Be it known that I, John J. Reinhold, a citizen of the United States, residing at Marietta, county of Lancaster, State of Pennsylvania, have invented a new, original, and ornamental Design for an Advertising Device or the like, of which the following is a specification, reference being had to the accompanying drawing, forming part thereof.

In the drawing:

Fig. 1 is a front elevational view of an advertising device, showing my new design;

Fig. 2 is a top plan view; and

Fig. 3 is a side elevational view thereof.

The broken line features are for illustrative purposes only.

I claim:

The ornamental design for an advertising device or the like, as shown and described.

JOHN J. REINHOLD.
